UNITED STATES PATENT OFFICE.

HANS SWANSON, OF WARREN, MINNESOTA.

INSULATOR ATTACHMENT.

No. 814,887.

Specification of Letters Patent.

Patented March 13, 1906.

Application filed April 26, 1905. Serial No. 257,516.

To all whom it may concern:

Be it known that I, HANS SWANSON, a citizen of the United States, residing at Warren, in the county of Marshall and State of Minnesota, have invented a new and useful Insulator Attachment, of which the following is a specification.

This invention relates to wire-clamping means for insulators of that class employed for stringing wire on overhead supports and the like, and has for its principal object to provide a novel means for rigidly clamping and holding a line-wire in such manner as to permit of the ready placing of the wire in position and its ready removal from the insulator.

A further object of the invention is to provide a device of this class in which the work of taking up slack, which must be accomplished more or less frequently on all lines, is rendered less difficult and expensive.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional elevation of an insulator provided with a wire-clamping means constructed in accordance with the invention. Fig. 2 is a sectional plan view of the same on the line 2 2 of Fig. 1.

Similar characters of reference are employed to indicate corresponding parts throughout both the figures of the drawings.

The insulator *x* is shown in the present instance as of that type of glass insulator extensively employed for overhead work and provided with a groove *y* for the reception of the tie-wire. In carrying out the present invention a loop 10, which may be formed of any suitable material—for convenience, a single or double loop of wire—is placed within the groove *y*, the loop being extended at one side to form a fulcrum for a cam-lever 11. This lever has a cam-shaped nose 12 for engagement with the line-wire *z*, and viewed transversely the cam-face is curved on a line corresponding to the curvature of the pe-

riphery of the insulator, no sharp edges being formed at a point which would tend to cut or otherwise injure the line-wire. The cam is provided with an elongated handle 13, which when in clamping position is disposed in an approximately vertical plane with the opening 14 or fulcrum-point of the cam at a point in a horizontal plane below the axis or center of the line-wire *z*, so that the tension of the supporting-loop 10 will automatically lock the cam in place and the wire will be firmly gripped between the nose of the cam and the inner wall of the groove, it being found in practice that the wire may be held with sufficient force to prevent any slipping under a stress less than that sufficient to break the wire. The rounded face of the nose 12 slightly curves the wire against the similarly-curved face of the insulator, and this to some extent adds to the efficiency of the clamp.

When placing the clamps in position, the loops, with the clamping-cams already in position thereon, are carried by the linemen, and the loop is simply slipped over the insulator, and after the line-wire is adjusted to position the clamp is forced from the dotted-line position shown in Fig. 1 to the full-line position shown in said figure and the operation is complete.

It is necessary at times to take up slack of the line-wires, and to accomplish this under ordinary conditions the usual tie-wires are cut, and after the wire is held taut new tie-wires are placed in position, this operation requiring considerable time and labor. With a clamp constructed in accordance with the present invention it is merely necessary to move the clamp from the full-line position shown in Fig. 1 to the dotted-line position and then after pulling the wire taut to move the clamp to locking position.

Having thus described the invention, what is claimed is—

1. A wire-clamp of the class described, comprising a cam-lever, a fulcrum-loop supporting the lever and adapted to surround the insulator, the cam being arranged to engage against the face of the wire, and the lever being movable to a locking position in a direction at right angles to the length of the wire.
2. A wire-clamp of the class described, comprising a cam-lever, and a fulcrum-loop arranged to surround the insulator, the wire-engaging face of the cam being concaved.
3. A wire-clamp of the class described, com-

prising an insulator - encircling loop, and a cam mounted thereon, the wire-engaging face of the cam being concaved to correspond to the contour of the periphery of the insulator.

5 4. A wire-clamp of the class described, comprising a loop for encircling the insulator, and a cam fulcrumed on the loop, said cam having a wire-engaging nose, the face of which is concaved to correspond to the curvature of 10 the insulator, the cam having an elongated

operating-handle arranged at a right angle to the length of the wire to be clamped.

In testimony that I claim the foregoing as my own I have hereto affixed my signature in the presence of two witnesses.

HANS SWANSON.
